UNITED STATES PATENT OFFICE.

AUGUST R. SCHOENKY, OF SOMERVILLE, MASSACHUSETTS, ASSIGNOR TO REECE SHOE MACHINERY COMPANY, OF BOSTON, MASSACHUSETTS, A CORPORATION OF MAINE.

DRIVING AND STOPPING MECHANISM.

Application filed July 23, 1919. Serial No. 313,733.

To all whom it may concern:

Be it known that I, AUGUST R. SCHOENKY, a citizen of the United States, residing at Somerville, in the county of Middlesex and State of Massachusetts, have invented a new and useful Driving and Stopping Mechanism, of which the following is a specification, reference being had therein to the accompanying drawing.

10 This invention is a novel driving and stopping mechanism, useful, for example, on power driven sewing machines, it being herein for the purposes of illustration shown applied to a shoe sewing machine known as the 15 welt-and-turn stitcher, which operates to attach the insole, and sometimes the welt strip, to the upper.

One object of the invention is to afford, by 20 pedal or other control, a designated maximum or high speed of drive, and a designated slow drive, the latter useful at the more difficult parts of the shoe. A further object is to permit a ready and easy shift of speed between the designated high speed and 25 the designated low speed. A further object is to give a satisfactory stopping of the machine by the throwing off of all power and the applying of a stopping means to give the correct final position of the parts, for 30 example, with the needle withdrawn from the work so as not to prevent the retraction of the work from the machine. A hooked, curved needle being employed in this particular class of machine, I contemplate also 35 the final disengagement of the thread from the hook, so as to wholly free the work for removal, but, as mechanisms for this additional purpose are shown in prior applications of mine, I make no disclosure or claim 40 thereof herein. An additional object of the present improvement is to effect an automatic opening or release of the thread tension or clamping device at the time of the stoppage of the machine. Further and more 45 particular objects and advantages of the present invention will appear in the hereinafter following disclosure of one embodiment thereof, or will be apparent to those skilled in the art.

50 To the attainment of the above referred to objects and advantages, the present invention consists in the novel driving mechanism and the novel stopping mechanism herein disclosed or claimed, and the novel features

of combination, arrangement, mechanism, 55 structure and detail herein described.

In the accompanying drawings, Fig. 1 is a left elevation of a shoe stitching machine embodying the driving and stopping mechanism of the present invention.

Fig. 2 is a front elevation thereof, with the stitching mechanism, however, omitted and the vertical machine frame or post broken away for concentration and enlargement of illustration.

Fig. 3 is a left elevation, partly broken away, of the drive mechanism at the base of the machine.

Fig. 4 is a plan view of the mechanism shown in Fig. 3.

Fig. 5 is a section taken on the line 5—5 of Fig. 3, looking from the rear.

Fig. 6 is a section taken on the line 6—6 of Fig. 4, looking from the left.

Fig. 7 is a central section of the disengaging clutch and stop means at the top of the machine.

Fig. 8 is a section taken on the line 8—8 of Fig. 7, looking from the right.

Fig. 9 is a plan view showing certain of 80 the thread tension releasing connections.

Above a base 11 extends upwardly the machine post 12, at the top of which is the frame part of head 13, which supports the stitching instruments and their operating 85 connections.

The prime source of power is the belt pulley 14, alongside of which is a loose pulley 15, both arranged on the forwardly extending power shaft 16. Through the driving 90 connections to be described, power is transmitted at high or low speed to the transverse shaft 17, which has a pulley 18, connected by drive belt 19 with a pulley 20, on the main or operating shaft 21 in the head 95 of the machine. The usual hand wheel 22 is shown at the left end of the main shaft. The stitching mechanism 23, driven from the shaft 21, includes the curved, hooked needle 24, and co-operating instruments, 100 which need not here be described, and the shoe rest or bumper 25.

At the front a pedal 27 is shown, which, as will be explained, controls the driving and stopping mechanisms. In Fig. 1 a pedal rod 105 28 is seen above the pedal, and thereabove a connected pedal rod 29, extending to the unclutching and stopping mechanism at the

top. At the rear of the head is seen the tension device 30.

The high speed connections, the low speed connections and the means for securing intermediate speeds, all of which are interposed between the power shaft 16 and the transverse shaft 17, are best shown in Figs. 3 and 4, reference also to be had to Figs. 2, 5 and 6.

10 The low speed connections include a worm 33 on the power shaft, and directly beneath this a worm wheel 34, the same mounted on the worm shaft 35, which near its left end has a gear 36, engaging the gear 37 on the shaft

15 17. The arrangement is such, as seen in Fig. 6, that the gear 37 may drive the transverse shaft at the low speed, and maintain it at that speed as a minimum, without, however, preventing the shaft from being driven

20 at a higher speed. In other words, a one-way engagement is provided. Rather than the noisy and ineffective toothed ratchet and pawl, I employ the plan shown in Fig. 6, in which a hardened steel ring 38 is secured

25 within the gear 37, while the hub 39 fast on the shaft 17 is furnished with three or more rollers 40, engaged in tapered recesses 41 in the hub 39. Each roller is adapted to be wedged between the narrow end of its recess

30 and the hardened ring 38. By this arrangement the gear, which is constantly turning in the direction of the arrow, will constantly drive the hub and shaft in the same direction unless the latter happen to be

35 rotating or driven at a higher speed by some other means. Such other means in the present machine is the high speed drive, which will next be described.

Referring back to Figs. 3 and 4, a friction 40 disk 44 is shown as splined on the power shaft, so as to rotate with it, but capable of axial sliding. Facing this disk is a second friction disk 45, which is loose on the power shaft, but capable of being driven by pres-

45 sure against its face by the other disk 44. Between the friction disks may be an intermediate friction disk bearing against both of them, as is frequently employed in this contrivance. By forcing the disks into mutual

50 contact the disk 45 is driven, and this through a bevel gear 46, carried by the disk 45, drives a bevel gear 47, mounted directly on the cross shaft 17. Obviously, whenever the disks are pressed together forcibly so as

55 to engage frictionally without slippage, the full speed drive is communicated from the power shaft to the cross shaft, and through the upwardly extending belt the main shaft will be driven at maximum speed.

60 When the friction disks are disengaged, the drag of the machine would tend to reduce the speed of the transverse shaft 17, which, however, cannot pass below that of the low speed drive connections 33—41. It is

65 sometimes desirable to expedite the retarding or speed reduction from the high to the low, especially for the purpose of abruptly stopping the machine when running at the maximum speed. For this purpose a braking device is employed, which may be of the following construction. A brake band 50, suspended at its upper end on a fixed bracket 51, surrounds a drum or flange 49 on the friction disk 45. As shown in Fig. 5, the brake has a pair of downward extensions 52, drawn forcibly together by a spring 53, which thereby tends to apply friction or drag to assist the speed reduction. The actual braking surfaces may be of felt, and may remain in action during the low speed 70 drive, without detriment. During high speed drive, however, it is advantageous to remove the braking pressure, and for this purpose a pair of toggle links 54 are shown, arranged to cause the spreading of the extensions 52 and the opening up of the brake band. This is done when the treadle 27 is depressed, a link 55 extending downwardly from the toggle links to an offset 56 on the pedal. The connections for controlling the 75 high and low speed drives, and incidentally for securing gradual variation of frictional pressure between the disks 44 and 45 to ease more or less the changes of speed above the the invariable minimum or slow speed are 80 preferably controlled from the pedal 27. For this purpose a block 59 having a wedge surface 60, and mounted to move axially on the power shaft in proximity to the friction disk 44, is in constant engagement with an 85 up and down moving block 61, having a wedge surface 62 bearing against the wedge surface 60. A spring 63 constantly pulls forwardly the axially moving block 59 to remove the pressure and friction between the 90 disks. A link 64 extends from the second wedge block 61 to the pedal. Thereby the depression of the pedal forces the block 59 and the disk 44 to the left to impose the desired friction. A spring 65 normally lifts 95 the pedal to the position shown in the drawings. When the pedal is depressed fully, that is, to the lowest dotted line position shown in Fig. 2, the full pressure between the disks causes maximum speed drive. 100 When the pedal is let up to the middle position shown, the frictional pressure is substantially removed, and the machine is driven at the low speed. By manipulating the pedal between said two positions, variations in friction and slippage may sometimes be introduced to give, to a certain extent, a control over the stitching speed, although usually the speed will be either the maximum or the predetermined minimum. 105

When, however, the pedal is let up completely from the middle to the topmost position shown, this, as will be explained, throws out the clutch at the head of the machine and applies the stop motion. It is 110

desirable that only the upper range of pedal movement, that is, from the middle to the top position, and not the lower range, shall move the pedal rod 29 which controls the 5 unclutching and stopping at the top of the machine. To this end the lower pedal rod 28 is provided at its upper end with a sliding block 68, confined beneath a guide plate 69 at the front of the machine. This block 10 has a pin 70, riding in a slot in the plate for guidance. The block also has a leftward offset or lug 71. This is for co-operation with a block 72, mounted at the lower end of the pedal rod 29. A pin 73 on the 15 block 72 engages a guide slot in the plate 69. Also the block 72 has an offset or lug 74, normally above the lug 71 on the other block, and a shoulder or projection 75 beneath the same. These parts may be designed 20 substantially as shown in Fig. 2, and the guide slot for the block 72 may have an inclined or cam portion 76 for throwing the block 72 to the left, out of operative engagement with the other block. By 25 this arrangement, when the pedal is depressed from the top to the middle position, the pedal rod 29 descends with the rod 28, owing to the engagement of lug 71 with the shoulder 75. The pin 73, however, 30 riding leftward into the cam slot 76, shifts the block 72 to the left, so that the shoulder 75 disengages the lug 71, and the further downward movement of the pedal leaves the upper pedal rod 29 stationary. The lug 71 35 slides against the righthand edge of the block 72, and thereby holds it in its disengaged position. When the pedal is again let completely up, the lug 71 strikes the lug 74, lifting it and causing the block 72 40 to rise and resume its illustrated position. By these described arrangements the pedal 27 gives complete control. In its lower range of movement, from middle to bottom, it is varying the speed between low 45 speed and high speed, or applying the high speed. In its upper range, from middle to top position, it is lifting or dropping the upper rod 29, which controls the unclutching and stopping of the main shaft of the 50 machine. This description brings us to the parts at the head of the machine.

The main shaft 21 is the operating shaft, which drives the stitching mechanism. This during stitching operations is driven 55 through the belt 19 and pulley 20, as before described, either at the maximum speed or at the low speed, or at some intermediate speed. Preferably, the drive is wholly thrown off or unclutched, not at the base 60 of the machine, but at the top, namely, between the pulley 20 and the shaft 21. For this purpose a frictional clutch 80, 81, is employed. Keyed on the shaft 21 is the disk 80, having an inclined inner clutch 65 surface opposed to the similar exterior

clutch surface of the friction ring 81, mounted directly on the pulley 20, as best seen in Figs. 2 and 7. The engagement and disengagement between the clutch members 80 and 81 is by a relative axial sliding. 70 Preferably, the pulley member 20 bearing the clutch ring 81 is axially movable, as well as being wholly loose upon the shaft. In Fig. 7 the clutch is shown disengaged; a very slight axial movement will serve to 75 engage it. For producing this movement, the grooved hub 82 of the pulley is engaged by the yoked end 83 of a clutch lever 84, having a fixed fulcrum 85 and a downward extension 86. For swinging this downward 80 extension a bent lever 87 is shown, fulcrumed at its lower end at 88, and pivoted at 89 to the lever 86. The lever 87 has a rightward extension 90, by which it is swung to cause the swinging of the clutch 85 lever. The extreme right end of the extension 90 is pulled upwardly by spring 91, which thus tends to close the clutch. The clutch, it will be understood, is to be closed whenever the control pedal 27 is in its lower 90 range of movement. When the pedal is let up to its top position, this throws open the clutch at the top of the machine. The following mechanism may be employed. A plunger or piston 93 is shown operating vertically within a hollow barrel 94. The lower or spindle portion 95 of the plunger is surrounded by a spring 96, tending to lift it. Externally at the bottom of the spindle is a head 97, which limits the upward movements. The rear side of the head 97 has connected to it a link 98, extending upwardly externally of the barrel to where it is connected to the arm 90 of the bent lever, which swings the clutch lever. The 100 relation of these parts can be observed in Fig. 1. At the top of the link 98 are adjusting nuts 99 for controlling the initial position of the parts, and thereby the relation of the clutch parts 80, 81. 105

The plunger and connected parts are shown in their downward position, which corresponds with the open condition of the clutch. When the plunger rises, it restores the clutch to closed condition. The spring 110 96 causes the rising. The means for depressing the parts will now be described.

On top of the plunger is movably mounted a finger 100. This, as seen in Fig. 7, is swingable from the full line position shown 115 to the dotted line position, at which latter it is inoperative. When it stands upright, as shown in full lines, it is operative. This swinging member or finger serves as a follower for a stop motion cam 101. This 120 cam constitutes the peripheral surface of the disk 80, forming one member of the clutch. The shape of the cam 101 is indicated in Fig. 8. It has a portion 102, which is shown in Figs. 7 and 8, and which serves 125 130

to hold the follower 100 downward to its lowest position, this being the final or stop position of the parts. When the machine is running, the follower stands to one side, 5 as shown in dotted lines in Fig. 7. When the machine is running, it is normally inoperative. When the pedal is let up completely and the time comes to stop the machine, the follower is caused to bear to the 10 left, as will be explained. It attempts to reach operative position against the periphery of the cam. As the figures indicate, however, this cannot be done, as the periphery is of such extended width as to serve 15 as a guard, except at the cam portion 103. This recessed peripheral portion permits the follower to assume operative position, always at approximately the same point in the shaft's rotation. Further around the 20 cam is the inclined surface 104, which, as will be explained, serves to give the final downward thrust to the plunger 93, and thereby apply a braking force upon the main shaft. The follower passes out of the 25 recess 103 by an inclined surface 105 to the guard portion 106.

The described operation of the cam follower is controlled from the pedal through the pedal rod 29, which, as described, rises 30 when the pedal is let up completely for stopping the machine. As shown in Fig. 2 and indicated in Fig. 7, the pedal rod is connected to a pair of toggle links 107, 108. It straightens the toggle links, and thereby 35 thrusts leftward a slotted arm 109, to which the link 108 is connected. The slot in arm 109 engages a pin 110 on the finger or follower 100. Thereby the lifting movement of the pedal rod tends to thrust the follower 40 from its inoperative dotted line position of Fig. 7 to its operative full line position of Figs. 2, 7 and 8.

The result is that, when the pedal is let up, the follower attempts to reach operative position, but can only do so at a certain point in the cycle, that is, when opposite the cam recess 103. The cam immediately thrusts downwardly the follower and plunger, thereby swinging the bent 45 lever 87 and opening the clutch 80, 81. The machine will then always come to a stop at approximately the same point in the cycle, for example, with the needle retracted from the work.

To ensure the accurate stoppage of the shaft, a final braking mechanism may be employed as follows. This utilizes the final downward thrust of the plunger 93, caused by the cam incline 104, which brings the 50 plunger beneath the final cam surface 102, as shown in the figures. The plunger has an extension 112, on which is mounted a T-shaped member 113, vertically adjustable by nuts 114. This member operates a pair 55 of toggle links 115, best shown in Fig. 8,

which serve to apply and release a brake band 116, surrounding the drum or braking surface 117 of the clutch disk 80, which is fast on the shaft 21. As seen in Fig. 8, the final downward thrust of the plunger 70 has pulled on the toggle levers, and thereby forcibly applied the brake band to bring the drum and shaft to a stop. The brake is lightly applied by the cam portion 101 before the disengagement of the lugs next 75 described.

Supplementary to the frictional action of the clutch 80, 81, I have provided a positive engagement in the form of a pair of engaging teeth or lugs 118, 118, mounted 80 respectively at the right end of the hub of pulley 20 and the left end of the hub of clutch member 80, as seen in Figs. 7 and 8. Thus, while preventing any slip during the normal action of the machine, and ensuring correct drive, notwithstanding the resistance of the work and stitching mechanism, the lugs 118 are readily and quickly disengageable when the clutch is opened, as in Fig. 7. This supplemental expedient 90 assists in ensuring that the final stoppage of the main shaft will be at the correct point in the cycle.

It remains only to describe the throwing open of the thread tension on the final 95 stoppage of the machine. The toggle arm 107, one of those which serves to thrust the stopping finger or follower towards its cam when the pedal rod 29 rises, is shown as provided with a downward arm or extension 119, see Figs. 7 and 2. Therefrom an adjustable connecting rod 120 extends to the right, to where it is connected to a swinging lever 121. This lever, as shown in Fig. 9, is fulcrumed at the rear of the 100 machine, and has a rearwardly extending tail 122, engaging in a notched sleeve 123, mounted between the thread wheel 124 and the tension spring 125. Normally the spring applies friction to retard the rotation of the thread wheel, and thereby restrain the drawing of thread. When the machine is stopped, the swing of lever 121 compresses the tension spring, and thereby wholly releases the thread to permit its being 110 freely drawn from the supply with the removal of the work from the machine. This occurs at the correct point in the final stitch cycle, as the follower 100 drops into the cam recess 103.

The stopping actions may be somewhat as follows. When the follower 100 drops in beneath its cam 101, this releases the tension, nearly one revolution before the final stop. As the follower rides out of the cam recess 125 103 by the cam incline 105, this applies lightly the final brake, which is rather an increased drag than a stopping brake. The clutch lugs 118 are still engaged and driving positively. This continues around the guard 130

surface 106. Next the final throw-down of the follower by the cam surface 104 puts the brake or drag into effect with full force and instantly the clutch lugs disengage, preferably the clutch opening connections being loose and delayed in action for this purpose. The machine, being of light momentum, and with its drag so greatly increased, now stops almost instantaneously on the cessation of drive, and without need of an impacting stop.

It will thus be seen that I have described driving and stopping mechanism, embodying the principles and attaining the advantages of the present invention. Since many matters of combination, arrangement, design, construction and detail may be variously modified without departing from the novel principles involved, no limitation to such matters is intended, except so far as set forth in the appended claims.

What is claimed is:

1. In a driving mechanism, a power shaft, an operating shaft, high and low speed connections, a pedal, connections from the pedal for controlling the high and low speed connections, a stopping clutch for the operating shaft, a pedal rod for controlling said clutch, and mechanism whereby the pedal actuates said rod only when the high speed is disengaged.

2. In a stopping mechanism a clutch, a clutch throw-out, a friction brake or drag, and cam control for applying the brake to increase the drag and then operating the clutch throw-out to give stoppage in a predetermined position.

3. In a driving mechanism, a power shaft, an intermediate shaft, and an operating shaft, in combination with high speed connections from the power shaft to the intermediate shaft, including a clutch, low speed connections from the power shaft to the intermediate shaft such as to maintain a minimum speed of rotation of the intermediate

shaft but to permit its being driven faster by said high speed connections, means for applying or releasing the high speed clutch to cause high speed or low speed drive, connections from the intermediate shaft to the operating shaft, including a clutch, and means for applying or releasing the last named clutch.

4. Driving mechanism as in claim 3 and wherein both said clutches are controlled by a single pedal or member, arranged so that the high speed clutch must be released and the low speed drive take effect before the other clutch is released.

5. Driving mechanism as in claim 3, and wherein a non-rotating brake operates automatically upon the release of the high speed drive to impose a drag to retard the intermediate shaft to the low speed.

6. Driving mechanism as in claim 3, and wherein a non-rotating brake operates automatically upon the release of the high speed drive to impose a drag to retard the intermediate shaft to the low speed, and wherein a single control member or pedal is employed, so arranged that when thrown it first causes the release of the high speed clutch and the application of the brake and thereafter the release of the other clutch.

7. In a driving mechanism operating between a power shaft and an operating shaft, the combination with said shafts, of a train of connections including a clutch by which high speed may be transmitted to the operating shaft, low speed connections such as to maintain a minimum speed when said clutch is released but permit a faster speed through said clutch, a drag means adapted to slow the operating shaft when said clutch is released, and another clutch adapted to wholly disengage power when released.

In testimony whereof, I have affixed my signature hereto.

AUGUST R. SCHOENKY.
